UNITED STATES PATENT OFFICE.

JOSEPH R. BLAINE, OF OAK PARK, ILLINOIS, ASSIGNOR TO MIEHLE PRINTING PRESS & MFG. CO., OF CHICAGO, ILLINOIS, A CORPORATION OF ILLINOIS.

PORTABLE ANTIOFFSET DEVICE.

Application filed March 28, 1921. Serial No. 456,258.

To all whom it may concern:

Be it known that I, JOSEPH R. BLAINE, a citizen of the United States, residing at Oak Park, in the county of Cook and State 5 of Illinois, have invented certain new and useful Improvements in Portable Antioffset Devices, of which the following is a specification.

My invention relates to printing presses 10 and particularly to an anti-offsetting device for use in connection therewith.

It is a well-recognized fact in the printing art that the ink which is impressed on sheets of paper in printing presses does not have sufficient time to dry between the time 15 the impression is made and the time the sheet is delivered to the pile. When printing is being done on glazed paper the ink requires a longer time to dry because of the 20 fact that the paper absorbs the ink less rapidly than when unglazed. Consequently, when printing on glazed paper it is necessary to insert slip sheets between adjacent sheets to prevent offsetting. This requires 25 not only the paper necessary to make the slip sheets but the time of operators to insert the sheets between the printed sheets.

One of the objects of my invention is to 30 provide an anti-offset device which will eliminate offsetting and avoid the use of slip sheets.

Another object of my invention is to provide an anti-offset device which is readily portable and may be applied to several 35 printing presses at the same time.

A further object is to provide an anti-offsetting device which will be simple to connect and operate.

A still further object is to provide an 40 anti-offset device in a portable form so that the same may be moved from one printing press to another, or brought into position to serve several presses at the same time to effectively prevent offsetting.

A still further object is to improve anti-offsetting devices for successful commercial use in connection with printing presses.

In carrying out my invention I have 50 shown in somewhat diagrammatic form the essential features thereof.

In Figure 1, I have shown the preferred form of my invention.

Figure 2 is a top plan view of a portion 55 of the apparatus shown in Figure 1; and,

Figure 3 is a sectional view through the

portable container of Figure 1 showing the same and means for creating the high frequency current in a diagrammatic form.

Carrying out my invention I utilize the well-known corona discharge placed in close 60 proximity to the printed sheet and provide means in portable form for creating radio frequency current necessary to make the corona discharge. In the drawings, 5 represents a printed sheet being carried on the 65 conveyor tapes 6 suitably mounted on rollers 7 and 8 of a printing press of any usual type. Sheet 5, it is understood, is being conveyed from the printing rolls to the pile table. Mounted above the sheet 5 is a board 70 9 carrying conductors having overlapping portions for the purpose of permitting a corona discharge, the conductors being arranged as shown in Figure 2, in which each end of the conductors terminates in binding posts 10 and 11, for connection by wires 12 and 13, with a source of radio frequency current. It is a well recognized fact that the present type of high potential current installation used for the purpose of removing 75 static electricity from printing paper is very dangerous, often times resulting in disastrous injuries to operators where such installations are being used. Furthermore, it is a well-recognized fact that radio frequency electricity can be conveyed only a limited distance as it is dissipated in the air and becomes ineffective. It is also a well-recognized fact that the installation necessary to supply radio frequency electricity 80 for a number of printing presses would be costly.

In carrying out my invention, to overcome the hereinbefore recited objections and to provide improved means for anti-offsetting, I provide a portable container 14 carried by a vehicle or truck 14^a suitably mounted on rollers 15 or equipped with suitable means to render it portable for movement about the printing shop as desired. Within the container 14 is mounted suitable means for furnishing a radio frequency current. Connection 16 adapted for insertion in an ordinary electric light socket, furnishes the source of energy to 95 the transformer A which is in the truck 14. Leading from the secondary portion of the transformer are the wires 17 and 18 having a spark gap 19 interposed therebetween. Each of the wires 17 and 18 terminates in 100 105 110

a condenser, the leads of which are connected to a Tesla coil 20, and from which coil conductors 12 and 13 extend for connection to the binding posts 10 and 11, on the board 5. If desired more than a single pair of conductors 12 and 13 may be led from the Tesla coil 20 to serve more than one printing press. Where the presses are arranged in battery form, it is possible to move the 10 container 14 between adjacent presses and connect each press with the source of radio frequency current therein. It will be observed that by mounting the radio frequency generating apparatus in a portable 15 container it is possible to move the same about the shop at will, and to make the conductors which convey the radio frequency current as short as is consistent with the installation of the same, so that the 20 loss of radio frequency current is reduced to a minimum. Furthermore, the use of my apparatus removes any chance for injury to the operators. It is possible to grasp the conductors 12 and 13 with the bare hand 25 without feeling any electrical effect whatsoever except warmth. The operation of the corona discharge is observed at the terminals of the conductors 12 and 13, which, of course, are insulated wires, as well as at 30 the antennae. It is the corona discharge that makes the ozone for oxidizing the ink on the newly printed sheet 5 as the same is being conveyed from the rolls to the pile table. If desired, by increasing the efficiency of the radio frequency current generating system, as many pairs of conductors 35 as desired may be led from the truck 14. It is a well recognized fact that it is not always necessary to provide means for anti- 40 offsetting the sheets being printed as weather

conditions control to some extent, as does also the class of printing being done. Therefore, with the installation embodying my invention, it is possible to disconnect the same whenever unnecessary for anti- 45 offsetting.

It is my intention to cover all modifications of the invention falling within the spirit and scope of the following claims.

I claim:

1. The combination with the conveyor for carrying printed sheets from a printing press, of means for generating ozone, said means being supported adjacent the path of the printed sheets, means for generating 55 radio frequency current, a portable support for said last-named means, and means for detachably connecting said radio frequency current generating means with said ozone generating means. 60

2. The combination with paper handling mechanism, of means for generating ozone, said means being supported adjacent the path of the paper handled by the mechanism, and means for generating radio frequency current associated with said ozone 65 generating means.

3. The combination with paper handling mechanism, of means for generating ozone, said means comprising a plurality of spaced 70 electrodes located in a plane, said electrodes being placed parallel to and adjacent the path of the paper handled by the mechanism, and means for generating radio frequency current associated with said ozone 75 generating means.

Signed at Chicago, Illinois, this 25th day of March, 1921.

JOSEPH R. BLAINE.
